Inventor:

Daniel R. Burns

UNITED STATES PATENT OFFICE.

DANIEL R. BURNS, OF DAYTON, OHIO, ASSIGNOR OF ONE-HALF TO FRANCIS J. McCORMICK, OF SAME PLACE.

STRAIGHT-WAY VALVE.

SPECIFICATION forming part of Letters Patent No. 255,717, dated March 28, 1882.

Application filed December 30, 1881. (No model.)

To all whom it may concern:

Be it known that I, DANIEL R. BURNS, a citizen of the United States, residing at Dayton, in the county of Montgomery and State 5 of Ohio, have invented certain new and useful Improvements in Straight-Way Valves; and I do hereby declare the following to be a full, clear, and exact description of the invention, such as will enable others skilled in the 10 art to which it appertains to make and use the same.

My invention relates to improvements in what is technically termed "straight-way valves;" and the object is to produce a straight-way valve that will prevent any leakage of water or other fluid when closed, and that will be 15 readily unseated when it is desired to open the valve.

The invention consists in a valve having two 20 disks which close the openings of the valve-chamber by being pressed against their seats by means of a pair of angular levers pivoted to a connecting-link on the valve-stem at one end and to lugs on the valve-disks at the other ends, 25 and bearing against a point on said disks with their downward-projecting ends, and by which they are firmly held in position when closed. To the lower sides of the valve-disks is attached a connecting-link, which prevents the valve- 30 disks from swinging inward on opening the valve-disks and holds them in a parallel position, and thereby prevents the obstruction of 35 the passage-way, all of which will be more fully described in the following specification, reference being had to the accompanying drawings, in which the figure represents a vertical cross-section of my improved valve in a closed position.

In the drawing, A represents the body or 40 shell of the valve, having the ordinary bonnet, A', and stuffing-box, and C C are the inlet and outlet openings, which are provided with a screw-thread or flange to connect them to the pipes or other desired place.

The stem H has a reduced end, over which 45 the cross-head or swivel g fits, and to this swivel are pivoted the angular levers a a. These levers are provided at their outer ends with slots b, that fit over pins B, secured to lugs D on the 50 two valve-disks, E, and permit the unseating

of said disks. The downward-projecting ends of the levers a a bear against the small points c on the valve-disks, and when the valve is closed firmly press said disks against their seats and prevent any possible leakage. The points 55 are preferably arranged centrally. At their lower sides the disks E are provided with slotted lugs e, to which a connecting-link, d, is attached by pins or bolts, and by means of which link the valve-disks are prevented from swinging 60 together, and are held in a parallel position when drawn away from their seats, and the valve is opened, thus preventing any obstruction of the passage-way. The slots in the lugs permit the valve-disks to become unseated 65 and prevent any binding action.

In the lower part of the case or shell A are arranged projections or recesses f, against which the lower edge of the valve-disks strike when they are forced down by the stem, which can 70 be operated by a screw and hand-wheel, or a lever pivoted to the stem.

It will be readily seen that instead of the angular levers being provided with slots, the lugs may be slotted and the levers bolted to them, 75 and the connecting-link may be made with a forked end and slotted, and the lugs be made solid, without departing from the spirit of my invention.

The valves can be made of any size to meet 80 the requirements.

The operation is as follows: When the valve-stem is raised the levers a a are first loosened from the pins c c, when the valve-disks will be unseated by means of the slots in them and the 85 lower lugs and by the pressure against the face of the valve-disks. As these are then raised into the space S above the opening C, the entire passage-way will be left unobstructed for the passage of the water or other fluid. When 90 it is desired to close the valve the stem with the disks will be forced down by the stem until they strike against the projections f, and the levers a will then come in contact with the pins c on the disks, and hold them firmly against 95 their seats, preventing any possible leakage, and until the valve is again opened.

By means of the levers bearing against the points c on the disks they can accommodate themselves to their seats, as the levers have 100.

only a very small bearing-surface, and the connecting-links *d* will retain the disks always in a parallel position. The valve-disks are shown in dotted lines when opened.

5 Having thus described my invention, what I claim, and desire to secure by Letters Patent, is—

- 10 1. In a straight-way valve, the connecting-link *d*, the valve-disks *E E*, having attaching-lugs, and the angular levers *a a*, connected to and operated by a valve-stem, arranged substantially as shown, and for the purpose set forth.
- 15 2. In a straight-way valve, the combination of the angular levers *a a*, the disks *E E*, having bearing-points *c c*, and the connecting-link *d*, attached to the lower sides of said valve-disks, all arranged for operation substantially as set forth.
- 20 3. In a straight-way valve, the combination

of the angular levers *a a*, pivoted to a swivel, *g*, on the valve-stem, and having slots *b*, with the valve-disks *E*, having bearing-points *c c*, and the connecting-link *d*, attached to slotted lugs *e e*, all arranged for operation substantially as specified.

4. The valve herein described, consisting of a shell, *A*, having openings *C C* and projections *f f*, the stem *H*, cross-head or swivel *g*, angular levers *a a*, the disks *E E*, having bearing-points *c c*, and the connecting-link *d*, attached as shown, and all constructed and arranged for operation substantially as shown and specified.

In testimony whereof I affix my signature in presence of two witnesses.

DANIEL R. BURNS.
